O. J. HAYES

CLOSURE FASTENER FOR RECEPTACLES

Filed Feb. 19, 1925

By *A. B. Gleeson & Co.*
Attorneys

UNITED STATES PATENT OFFICE.

ORVILLE JOSEPH HAYES, OF DECATUR, ILLINOIS.

CLOSURE FASTENER FOR RECEPTACLES.

Application filed February 19, 1925. Serial No. 10,371.

To all whom it may concern:

Be it known that I, ORVILLE JOSEPH HAYES, a citizen of the United States, residing at Decatur, in the county of Macon and State of Illinois, have invented certain new and useful Improvements in Closure Fasteners for Receptacles; and I do declare the following to be a full, clear, and exact description of the invention, such as will 10 enable others skilled in the art to which it appertains to make and use the same.

This invention relates generally to receptacles, but particularly to closure fasteners for receptacles such as egg crates, shipping 15 cases, and the like.

The objects of the invention are to provide a device of the character described which will lock automatically when the closure member is applied to the receptacle 20 member and which will not become accidentally unlocked, but which may be very easily released. The device contains no loose parts and nothing to break or wear out, so that it will always be ready for use.

In further describing the invention, reference will be made to the accompanying drawing which illustrates a practical embodiment of the invention.

In this drawing:—

Figure 1 is a perspective view of an egg crate provided with closure fasteners constructed in accordance with the principles of the present invention, the view showing the closure member about to be applied to 35 the receptacle member;

Figure 2 is a perspective view of one end portion of the crate, showing the closure member applied and locked upon the receptacle member;

Figure 3 is a perspective view of a portion of one of the cleats with which the receptacle member is provided;

Figure 4 is a similar view of a portion of one of the cleats with which the closure 45 member is provided;

Figure 5 is a vertical sectional view through a portion of one end of the crate, showing the closure member applied and locked upon the receptacle member; and

Figure 6 is a plan view of a portion of one of the cleats with which the receptacle member is provided.

In the illustrated embodiment of the invention, the numeral 1 designates a receptacle member of the type generally used as

an egg crate or shipping case. This member 1 is open at the top, and secured to its ends along the upper edges of such ends are cleats 2. These cleats 2 are provided intermediate of their ends with notches 3 having transverse or vertical walls 4 forming shoulders, and these shoulders are formed with semi-circular or other suitably shaped grooves 5. Rigidly secured at one of their ends to the cleats 2 are resilient strips 6. The other ends of these strips 6 extend across the notches 3 toward the transverse or vertical walls of said notches and the grooves 5, and are adapted to be received in the notches when depressed.

The lid or closure member for the device is represented by the numeral 7, and upon referring to the drawing, it will be seen that this member is provided along its end edges with cleats 8. These cleats 8 are adapted to fit against the end walls of the receptacle member 1 when the lid member 7 is applied to the latter, and also to have their lower edges abut the upper edges of the cleats 2. Secured to the cleats 8 intermediate of the ends thereof are rigid pins 9. These pins 9 are positioned so as to be inserted in the aforesaid grooves 5 and be engaged by the free ends of the resilient strips 6, when the closure member 7 is applied to the receptacle member 1. When the pins 9 are inserted into the grooves 5, their free ends will depress the free ends of the resilient strips 6 to a certain extent, but when the free ends of the strip 6 snap past the ends of the pins 9, they will engage the sides of the pins 9 and prevent the latter from being withdrawn from the grooves 5.

From the foregoing description taken in connection with the accompanying drawing, the construction, use and advantages of the invention will be readily understood. It will be seen that in order to lock the closure member 7 upon the open top of the receptacle member 1, it is simply necessary to apply the former to the latter, as the strips 6 upon being depressed the required amount automatically engage the adjacent sides of the pins 9 and lock the latter against withdrawal. Although the strips 6 will so firmly lock the pins 9 that the closure member 7 will not accidentally become loose or unlocked, yet the closure member 7 may be very easily unlocked and removed simply by inserting the finger in the notches 3 above

the free ends of the strips 6 and depressing such strips. The depression of the strips to permit release of the pins is permitted through forming the strips of less length than the inclined bottom portions of the notches.

Various changes in form, proportion, and in the various features of construction, may be made without departing from the spirit and principle of the invention or without sacrificing any of the advantages thereof, so that it is to be understood that certain changes may be made within the meaning and scope of the appended claim.

15. I claim:—

In a closure fastener comprising, a member having a recessed front with an inclined bottom portion and a shoulder at the lower

end of the inclined portion, said shoulder extending outwardly to a point in a plane 20 with the upper end of the inclined end having a central outwardly extending groove, a resilient strip having one end secured to the member adjacent the upper end of the incline and normally extending toward the 25 outer end of said shoulder and spaced therefrom, a rigid pin slideable in said groove to flex the strip and engage the free end of the latter with the side portion of the pin, said strip being in holding position at a 30 point spaced from the inclined bottom and movable into contact with the latter to permit release of the pin.

In testimony whereof I have hereunto affixed my signature.

ORVILLE J. HAYES.
